United States Patent Office

Des. 189,351
Patented Nov. 29, 1960

189,351

COVER FOR A WALL OUTLET

Betty J. Story, 124 Garrett St., Chula Vista, Calif.

Filed Sept. 1, 1959, Ser. No. 57,398

Term of patent 14 years

(Cl. D26—13)

Fig. 6

Figure 4 is an end elevational view thereof, both ends being similar;

I claim:

The ornamental design for a cover for a wall outlet, as shown and described.
